UNITED STATES PATENT OFFICE.

OLIVER H. CLARK, OF DETROIT, MICHIGAN, ASSIGNOR TO CHRYSLER CORPORATION, OF DETROIT, MICHIGAN, A CORPORATION OF DELAWARE.

DESIGN FOR A RADIATOR SHELL.

Application filed November 21, 1927. Serial No. 24,219. Term of patent 14 years.

To all whom it may concern:

Be it known that I, OLIVER H. CLARK, a citizen of the United States, residing in the city of Detroit, in the county of Wayne and State of Michigan, have invented a new, original, and ornamental Design for Radiator Shells, of which the following is a specification, reference being had to the accompanying drawing, forming a part thereof, in which—

Fig. 1 is a front elevation of a radiator shell embodying my design.

Fig. 2 is a side elevation thereof.

Fig. 3 is a cross section of the radiator shell.

I claim:

The ornamental design for a radiator shell, as shown.

OLIVER H. CLARK.
